UNITED STATES PATENT OFFICE.

CHARLES W. HUNT, OF WEST NEW BRIGHTON, ASSIGNOR TO THE C. W. HUNT COMPANY, OF NEW YORK, N. Y.

VALVE-GEAR FOR STEAM-ENGINES.

SPECIFICATION forming part of Letters Patent No. 437,928, dated October 7, 1890.

Application filed February 3, 1890. Serial No. 339,062. (No model.)

To all whom it may concern:

Be it known that I, CHARLES W. HUNT, a citizen of the United States, residing at West New Brighton, in the county of Richmond 5 and State of New York, have invented an Improvement in Valve-Gears for Steam-Engines, of which the following is a specification.

The present invention relates to a valve-gear in which the valve receives its motion 10 from levers and links and can be moved to cause the engine to revolve in either one direction or the other or to stop.

In the drawings, Figure 1 is an elevation 15 of the valve-gear. Fig. 2 is a diagram illustrating the positions of the parts and the lines of movement. Fig. 3 is a section representing the relative positions of the piston and the links extending from the cross and connecting rod. Fig. 4 is a plan view of the 20 connections to the valve-rod, and Fig. 5 is a diagram representing a modification.

The cylinder A, piston-rod B, cross-head C, and connecting-rod D to the crank-pins 3, and crank C² are of ordinary character. The connecting-rod D has a downwardly-projecting 25 arm D', to which one end of the link E is connected, that extends to the rocker F, and there is a second link L connecting this rocker F with the cross-head C. The rocker F is pivoted to and suspended by a radius-bar G, and this radius-bar is connected by the joint or pivot 4 to the valve-rod N, and such valve-rod passes through the slide N', so that its outer 30 end is supported. It may be preferable to 35 fork the valve-rod N and the radius-bar G, as seen in Fig. 4, so that the actuating-link H is pivoted at 5 within the jaw of the radius-bar G, and so that the strain comes in one line. The end 10 of the rocker F is connected to 40 the link K, in order to give the arm H a vibratory motion upon the center 5.

At the end of the link H is a block P, which slides within the slotted sector O or its equivalent. The sector O may occupy the position 45 shown in Fig. 1, or it may be moved into the position indicated by the dotted lines 7 or 8, Fig. 2.

By reference to the diagram Fig. 2 it will be understood that when the engine is in motion 50 the pivot 2 of the rocker F will swing in

the arc of a circle, and the joint 10 of the rocker F will describe the figure of a crescent, as indicated by the dotted lines, Fig. 2, and in so doing the link H may be swung up and down upon the arc of the circle 11, which being described from the joint 5 will not cause the link H to move endwise, but in consequence of the joint 4 of the radius-bar G being at a little distance from the joint 5 the valve-rod will receive a slight endwise motion which is to be sufficient for the lap and lead of the valve. If now the sector O is moved into the position indicated by the dotted lines 7, an endwise motion will be given to the link H by such sector, and the valve will 60 be moved for the engine to rotate in one direction, and if the slotted sector O is moved into the position indicated by the dotted lines 8, Fig. 2, the motion given to the valve will cause the engine to rotate in the other direction, the movement in either instance being given by the slotted sector O and the block P that slides therein in consequence of the swinging motion given to the link H by the link K, as the lower end of the link K at the 75 joint 10 is caused to describe a crescent shape by the movement of the connecting-rod, cross-head links, and rocker, as aforesaid.

By the diagram Fig. 5 it will be understood that a link O² may take the place of 80 and be the equivalent of the sector. In this case the link is of the same length as the radius of the sector, and by moving the pivot of the link to the point 15 the joint 16 will describe the arc 7, and by moving such pivot 85 15 to the point 18 the joint 16 will describe the arc 8, and the operations will be the same as before described.

It will be evident that in this valve motion there are two parallelograms C' D' 2 12 and 90 2 10 5 17, and these acting together cause the link H to swing and remain parallel, or nearly parallel, with the connecting-rod D, as the latter is carried up and down with the crank C², and the movement given to the valve is 95 similar to that from an eccentric.

I claim as my invention—

1. The combination, with the valve-rod supported at its outer end, of the radius-bar G, pivoted to the end of the valve-rod, and 100

actuating-link H, pivoted to the radius-bar, the slotted sector or its equivalent for moving the link H endwise, the link K, rocker F, links E and L, cross-head, connecting-rod, and arm D' for giving motion to the respective parts, substantially as set forth.

2. The combination, with the valve-rod, the cross-head, connecting-rod and crank, of the link G, pivoted to the valve-rod, the link H, pivoted to the link G at a sufficient distance from the connection of the link G to the valve-rod to give to the valve the necessary

lap and lead movement, the sector O or its equivalent for moving the link H endwise, and a connection to the connecting-rod for swinging the link H laterally, substantially as set forth.

Signed by me this 25th day of January, 1890.

CHAS. W. HUNT.
